UNITED STATES PATENT OFFICE.

JOHN LAFOUREADE HAMILTON, OF BOSTON, MASSACHUSETTS, ASSIGNOR TO SAFAND-SHUR CHEMICAL CO., INC., OF NEW YORK, N. Y., A CORPORATION OF NEW YORK.

CONTAINER.

1,378,674.

Specification of Letters Patent. Patented May 17, 1921.

Application filed October 25, 1920. Serial No. 419,465.

To all whom it may concern:

Be it known that I, JOHN L. HAMILTON, a citizen of the United States, and a resident of Boston, in the county of Suffolk and 5 State of Massachusetts, have invented a new and Improved Container, of which the following is a full, clear, and exact description.

This invention relates to containers for fire extinguishing fluid and has for an object 10 to provide an improved construction where- in the fluid is maintained sealed under ordinary circumstances, but which may be unsealed and the container opened quickly by the same movement which transmits the container to a point adjacent a fire.

Another object of the invention is to provide a container and supporting arrangement forming part of the container which 20 includes a lid designed to be fixed substantially stationary while the body of the container is frictionally held against the lid in such a manner as to be readily removed by a swinging lateral movement of the container.

25 Another object, more specifically, is the arrangement of a container having a perforated end and a cap normally closing the end with means extending through the cap for clamping the cap to a wall or other support 30 so that the container may be pulled therefrom quickly and easily.

In the accompanying drawing:

Figure 1 is a perspective view showing an embodiment of the invention being removed 35 from a supporting wall.

Fig. 2 is a vertical sectional view through the upper part of a container disclosing an embodiment of the invention.

Fig. 3 is a perspective view of the cap 40 shown in Fig. 2.

Referring to the accompanying drawing by numerals, 1 indicates a container of any desired size, and provided with a solid bottom of any desired structure so as to readily 45 contain the liquid 2, which is a fire extinguishing fluid of some good quality, and which will vaporize or gasify when discharged in a comparatively finely divided state. The container 1 is provided with a 50 special end member 3 having perforations 4, which has the material from the perforations pressed outwardly for forming what may be termed dispersing or dividing prongs 5. These prongs are in the path of move-

ment of the liquid as it passes through the 55 apertures 4, and will assist in dividing the liquid into small streams or into a spray condition whereby the liquid will reach the fire in a more or less vaporous or gaseous condition and thereby produce quickly a 60 swelling blanket.

The end member 3 is rigidly secured to the container 1 so as to be air-tight, but in order to seal the container over the openings 4 a cap 6 is provided formed with an annular 65 depending embossed portion 7 resting against a gasket 8. This provides a sealing member so as to maintain the liquid 2 in the container and prevent any appreciable evaporation thereof even though the container is 70 left in one place a long period of time. The cap 6 extends upwardly and beyond the container 1 so that a supporting screw 9 may be forced through the apertures 10 and 11 formed in the upper part of the sides of the 75 cap. If desired a covering plate 12 may be connected with the sides of the cap for producing a finished appearance as shown in Fig. 3.

In operation, when the cap and container 80 are assembled as shown in Fig. 2 with the liquid 2 in place the device is ready to be applied to a suitable support. In order to apply the device to a support the screw 9 is inserted through the apertures 10 and 11 85 and is screwed into a wall or other support as shown in Fig. 1. The container 1 is left hanging in this position until it is desired to use the same, said container being supported by the friction between the end member 3 and the walls of the cap 6. A direct downward pull will cause the container to slip off the cap, though usually the cap is rather tight and consequently will require an extra downward strain if used. Preferably 90 the container is grasped as shown in Fig. 1 and pulled downwardly and laterally at the same time whereby a prizing action will cause the container to easily leave the cap 6, and when this has been done it is in 100 condition for use. The liquid is not merely poured on the fire, but the container is moved back and forth toward the fire more or less rapidly and the liquid is ejected through the openings 4 with considerable force, and 105 as it passes the spurs 5 will be more or less divided and consequently form a blanket cloud of vapor or gas quickly.

What I claim is:—

1. A container for fire extinguishing liquid comprising a body for receiving a liquid, a cover formed in said body having 5 perforations therein arranged so that the material pressed therefrom forms spurs extending outwardly whereby when the liquid is passing through said perforations the spurs will finely divide the same so as to 10 produce a better distribution in a minimum time, a gasket arranged on said cover, and a cap engaging said gasket for sealing the end of the container carrying said perforations.
- 15 2. A container for fire extinguishers comprising a body having an opening at one end provided with a foraminous plate extending across the opening spaced from the end of the container, a gasket arranged on said 20 foraminous plate adjacent the sides of the container, a cap formed with an annular depending flange adapted to press against said gasket for sealing the end of the container, and a supporting member extending 25 through part of the cap.
3. A container for fire extinguishers comprising a body having an opening at one end provided with a foraminous covering, a gasket arranged on said foraminous covering, a cap fitted into said container and resting against said gasket, said cap being 30

provided with upstanding walls projecting beyond the container and provided with diametrically opposite openings, and a supporting member extending through said 35 openings, said supporting member being formed with a head for preventing accidental disengagement.

4. A container for fire extinguishers comprising a body having an opening at one 40 end, a covering member for said opening having a plurality of perforations therein with spurs arranged adjacent the perforations so that the liquid from the container passing through said perforations will be 45 finely divided by said spurs, a cap for covering said perforated member, and means engaging the cap for connecting the same firmly to a support.

5. A container for fire extinguishers comprising a body having an open end, a foraminous member arranged across said open end, a cap for covering said foraminous member, said cap being formed with an annular upstanding wall provided with a pair 55 of apertures arranged diametrically opposite, and a headed screw extending through said apertures connecting the cap to a support, the head of the screw engaging the cap for preventing any disengagement of the 60 cap.

JOHN LAFOURADE HAMILTON.
